(57) **CLAIM**

The ornamental design of the razor handle, as shown and described in the foregoing drawings.

DESCRIPTION

FIG. 1 is a top perspective taken from the left side of the razor of the present invention;

FIG. 2 is a top plan view of the razor of FIG. 1;

FIG. 3 is a left side view of the razor of FIG. 1, the right side view being the mirror image thereof;

FIG. 4 is a bottom plan view of the razor of FIG. 1;

FIG. 5 is a front elevational view of the razor of FIG. 1;

FIG. 6 is a back elevational view of the razor of FIG. 1; and, FIG. 7 is a the same perspective view of the razor of FIG. 1 adding a cartridge in phantom.

The broken line showing the cartridge is for illustrative purposes only and forms no part of the claimed invention.
